John H. Peery

UNITED STATES PATENT OFFICE.

LEO ENGEL, OF ASBURY PARK, NEW JERSEY.

STATION FINDER FOR TIME TABLES.

Application filed March 14, 1925. Serial No. 15,421.

To all whom it may concern:

Be it known that I, LEO ENGEL, a citizen of the United States, and a resident of Asbury Park, county of Monmouth, and State of New Jersey, have invented a certain new and useful Improvement in Station Finders for Time Tables, of which the following is a specification.

The object of this invention is to provide an article intended to be used in connection with railroad time tables or the like, to enable the user of the same to more readily locate train data appearing on the time table. The tables in use at the present time are of considerable length and bear a list of the stations near one of their ends. It is with considerable difficulty that a person is able to trace the time at which the various stations are reached by the various trains, especially when the data regarding a particular train is located at some distance on the sheet from the point where the list of stations is located on the table. The main object, therefore, of this invention, is to provide a simple and inexpensive device which will bear the list of stations as they appear, in both directions, and which may be moved on the time table to a position adjacent to the data appearing thereon relating to any train in which the user may be interested, thus enabling the user to ascertain all of the facts regarding the train without having to trace the various stations across the time table.

With these objects, and such other objects as may hereinafter appear, in view, I have devised the particular arrangement of parts hereinafter set forth and more particularly pointed out in the claims appended hereto.

Reference is to be had to the accompanying drawing, forming a part hereof, in which—

Figure 1 is a plan view of a portion of a time table, showing my improved finder as the same appears when in use;

Figure 2 is a sectional view on the line 2—2 of Figure 1, looking in the direction of the arrows;

Figure 3 is a plan view of one end of the finder showing the same in an unfolded or flat position;

Figure 4 is a perspective view of the finder, showing the opposite side of the same to that shown in Figure 1, and

Figure 5 is a perspective view clearly showing the central slot with which the finder is provided, and through which the time table is adapted to be moved.

Throughout the various views of the drawings, similar reference characters designate similar parts.

In the preferred embodiment of my invention, as disclosed in the accompanying drawing, I have shown my improved finder as being composed of a single sheet or piece of thin and flexible material, such as strong but flexible pasteboard, celluloid, fibre or thin metal. The same is composed of two flaps 1 and 2, which are of greater length than the width of the time table on which the article is intended to be used. At 3 is indicated a fold line which is located between the flaps, and the device is intended to be longitudinally folded upon this line 3. Located directly upon the fold line 3 is a slit 4, which is of greater length than the width of the time table, and said slit 4 is provided with enlarged ends 5, so that tearing or enlarging of the slit at its ends during the use of the article is prevented.

On the face of the flap 1 is provided a list of stations 6 which list corresponds to the list of stations appearing on the time table at 7. On the rear face of the flap 2 appears a list of stations appearing on the time table at 8 in reverse order to those appearing on the list indicated at 6.

The manner in which the article is used will be readily apparent from the foregoing. The time table 8 is passed through the slit 4 and the flaps 1 and 2 are folded with respect to one another so that the list of stations 6 on the flap 1 appears over the list 7 on the time table. Assuming that the user is interested in the train data appearing as at 9. To use the finder, he simply moves the same along on the time table, or draws the time table through the slit 4, until the list of stations 6, appearing on the flap 1 becomes located in juxtaposition to the train data 9. If interested in trains going in the opposite direction, the time table is turned over on its opposite face, where the list of trains going in the desired direction usually appears, and without withdrawing the time table from its position in the slit 4, the flaps 1 and 2 are folded back against one another so that the list of stations appearing on the flaps 2 at 8

is outermost. This list 8 corresponds to the list 10 appearing on the back face 11 of the time table, and the finder is moved along until it lies adjacent to the data affecting the train in which the user is interested.

Having described my invention, what I claim is:

1. An article of the class described comprising a sheet having a pair of reversible flaps separated by a single fold line, a slit on said fold line through which a time table is adapted to be inserted, a list of stations on one of said flaps corresponding to a list of stations appearing on one face of the time table, and a list of stations on the other flap corresponding to a list of stations appearing on the other face of the time table.
2. An article of the class described comprising a sheet formed with two connecting flaps, a fold line between the flaps, a slit on the line of said fold, and a list of stations on each of said flaps.
3. An article of the class described comprising a sheet folded to form a pair of flaps, a slit in said sheet through which a time table is adapted to pass, a list of stations on one of said flaps and a list of stations on the other flap appearing in a reverse direction to those on the first mentioned list.

4. An article of the class described comprising a sheet folded to form a pair of connected flaps, a slit extending longitudinally of the sheet and located on the line of the fold, a list of train stations appearing on one face of one of the flaps, and a list of stations arranged in reverse positions appearing on the back face of the other flap.

5. An article of the class described comprising a sheet of flexible material having a central longitudinally extending slit through which a time table is adapted to pass, said sheet being adapted to fold on the line of said slit, a list of stations on one face of the sheet adjacent to the slit, and a list of stations in reverse position on the back face of the sheet adjacent to the slit.

6. An article of the class described comprising a sheet divided to form a pair of flaps, a slit located between said flaps, a list of stations on one face of the sheet adjacent to the slit and a list of said stations in reverse order on the opposite face of the sheet adjacent to the slit.

Signed at the city of New York, county of New York and State of New York, this 13th day of March, 1925.

LEO ENGEL.
